UNITED STATES PATENT OFFICE.

LEONIDAS H. VAN SYCKLE, OF FORT LEE, NEW JERSEY, ASSIGNOR TO
HIMSELF AND JOHN F. CREAMER, OF SAME PLACE.

CARTRIDGE-LOADING MACHINE.

SPECIFICATION forming part of Letters Patent No. 336,676, dated February 23, 1886.

Application filed June 17, 1885. Serial No. 168,997. (No model.)

To all whom it may concern:

Be it known that I, LEONIDAS H. VAN SYCKLE, of Fort Lee, in the county of Bergen and State of New Jersey, have invented an improvement in Cartridge-Loaders, of which the following is a specification.

This invention is for supplying into a cartridge shell or case powder and then a wad, and then introducing shot, the shot and powder being measured for determining the proper quantity.

Before my invention cartridge-loading implements had been manufactured for introducing powder and then shot.

My improvement is for simplifying the construction of the parts and for accurately measuring the powder and shot, respectively, and for facilitating the insertion of the wads between the powder and shot and at the end of the case, respectively.

In the drawings, Figure 1 is an elevation of the loading apparatus complete. Fig. 2 is a plan view of the same with the rammer in section. Fig. 3 is a section vertically through the holder for shot. Fig. 4 is a sectional plan at the line $x-x$ of Fig. 1. Fig. 5 is a vertical section through the plunger and cartridge-case. Fig. 6 is a detached view of the holder for the wad. Fig. 7 is a sectional plan through the shot-measure above the valve. Fig. 8 is a similar section through the powder-measure. Fig. 9 is a rear view of the powder-measure; and Fig. 10 is a separate view of the swinging base for the cartridge-case.

I provide a vertical tube, A, within which is a plunger, B, with a suitable head for driving the plunger down and ramming the powder or the wad into the cartridge-case C. The tube A is supported by an arm or bracket, A', projecting from a frame or plate, A², and the lower portion of the tube A is removed at one side to allow for the insertion or removal of the cartridge-case C, and there is a swinging base, D, forming a support for the cartridge-case. This base D is turned aside upon the pivot d , to allow the cartridge-case to be easily inserted or removed, and this swinging base D is passed in beneath the cartridge case to raise the same and hold it up into place; and with this object in view the swinging base D is made with a segmental wedge, d' , for raising the cartridge-case as the swinging base is turned, and it is preferable to make the swing-

ing base with a cavity beneath the fulminate or cap, so that there will not be any pressure against the cap while charging the cartridge. The plunger B is made with a groove, b, at one side, and in this groove there is a cam-shaped piece, b', and E is a spring connected upon the outside of the tube A, and the end 6c of this spring passes into the groove b, and said spring will sustain the plunger B when the cam b' passes up beyond the end of said spring E; but the spring yields to the action of the cam when the plunger is driven down. The 65 stop-finger b', upon the tube A, in a groove in said plunger, prevents the plunger being drawn out of the tube A.

At one side of the tube A, and parallel with and attached to the same, is a cylinder, F, that 70 is open at the top end and is slotted longitudinally, and said cylinder F rests at its lower end upon a plate, f, to which it is attached. The vertical tube A has an opening in the side in line with the surface of the plate f, and there 75 are spring-fingers e connected with the lower end of the cylinder F, which fingers yield to allow a wad to be pressed into the cylinder A from off the plate f, and they hold the wad by its edges until the plunger is driven down upon 80 the wad to carry it down into the cartridge-case C. This plate f is slotted in a line with the center of the tube A, and the springing wad-pusher G passes, at its upper end, through 85 this slot. This wad-pusher G is in the form of a lever, pivoted at g and thrown back by the spring h. The wads themselves are of ordinary character, and the spring wad-carrier H is in the form of a thin sheet-metal tube, open longitudinally at one side, and provided with 90 clips or finger-pieces h', projecting near one end. The other end, h², of the wad-carrier is closed. The wads themselves are thrown into this carrier and pressed toward the closed end h², so as to lie in their proper relative positions, 95 and this carrier forms a gage by which to detect washers that may be of the wrong thickness, by counting the numbers that lie side by side in said carrier. The finger-pieces h' are grasped and compressed, so that the wads themselves are held from falling out of the carrier while the carrier is inverted and passed into the slotted cylinder F, the wads are thus brought to the proper position to form a pile of wads, the lower one of which rests upon the 100 plate f, and such bottom wad of said pile can

be carried off laterally whenever required, by moving the wad-carrier H, which forces the wad along between the spring fingers e into the tube A, immediately over the upper end 5 of the cartridge-case C, so that said wad can be forced down into said cartridge-case by the plunger B.

The hopper or holder K is for powder, and the hopper or holder L is for shot. Below 10 the powder-hopper K is a vertical measure, k, and there is a similar measure, l, below the shot-hopper. The pipe k' leads the powder from the measure k to an opening at one side of the tube A, and a similar pipe, l', leads the 15 shot from the measure to an opening at the opposite side of the tube A. In the bottom of the hopper K is a swinging cut-off, n, which is immediately below the hopper bottom of said powder-holder K, and there is a spring, n', to 20 move this cut-off back from beneath the opening at the bottom of the hopper K. The powder measure k is beneath the opening in the hopper and also below the swinging cut-off n. At 25 one side of this measure k is a vertical slot, through which passes a plate of metal, o, and upon this plate o is a valve, o', of a size adapted to form a bottom to the measure k when turned 30 up horizontally, and around the outside of the measure k is a sliding band, o'', having a pivot wire or pin, 2, passing through the plate o, and upon which pivot the valve o' can be 35 swung. This band o'' can be raised or lowered, and with it the valve o', so as to vary the capacity of the powder-measure, and this band o'' is held in the position to which it may be 40 adjusted by a spring, 3, attached to the band o'', and springing into notches at the corner of the powder-measure, as seen in Fig. 9. There 45 is a bent lever, P, pivoted upon the band o'', and one end of this bent lever is connected 50 with the plate o by a pin passing through a hole in that plate, and there is a spring, p, that acts against the lever P to hold the same in its normal position and to close the valve o'. This lever P is acted upon by the swinging 55 cut-off n after the cut-off has closed the opening at the bottom end of the powder-hopper K, so that the powder has been cut off from the hopper, the bent lever P is swung, and the 60 valve o' tipped to discharge the powder from the measure, and allow it to run from the measure by the pipe k' into the tube A and the cartridge-case at the bottom of the same. The hopper L for the shot and the measure 65 below the same are provided with a swinging valve, q', upon a plate, q, that is pivoted to a band, q'', around the shot-measure l, and r is a bent lever that acts upon the valve q' to tip the same and discharge the shot from the 70 measure l into the tube l', so that said shot runs into the vertical tube A and the cartridge-case placed at the bottom of the same. These parts are constructed and operate substantially the same as those which have been described 75 for measuring and supplying the powder. The band q'' and valve q' may be adjusted by a movable pin passing through holes in a verti-

cal plate, q', fastened to the bottom of the hopper L. It is, however, important to prevent the shot obstructing the movement of the 70 cut-off s. I therefore combine with the hopper L and cut-off a spring finger, t, formed of a loop of wire extending downward into the opening at the bottom of the shot-hopper L, and this spring finger is just above the surface 75 of the cut-off s, and it loosens and supports any shot that might otherwise be immediately adjoining the point where the cut-off finally closes against the lower edge of the hopper, and prevents a shot becoming wedged into 80 such opening as the cut-off is closed.

Graduations may be engraved or marked upon the surface of the measures k l to indicate the quantity of powder or shot.

I am aware that a yielding finger has been 85 applied at the surface of the slide to allow the shot to pass beneath it, and that this has been located outside the hopper and also between the hopper and the slide. When placed within the hopper, as in my present improvement, it 90 serves to prevent shot passing from the hopper down at the edge of the plate that forms the slide.

I claim as my invention—

1. The combination, with the tube A and 95 plunger B, of the swinging base D, having a segmental wedge, d', for raising and holding the cartridge-case C at the lower end of the tube A, substantially as set forth.

2. The combination, with the vertical tube 100 A and plunger B, of the slotted cylinder F, attached to the vertical tube A, the slotted wad-carrier H, the slotted plate f, to support the wads, the spring-fingers e, attached to the stationary cylinder F, and having their spring 105 ends at opposite sides of the tube A, and the swinging wad-pusher G, substantially as set forth.

3. The combination, with the tube A, plunger B, cylinder F, and pusher G, of the wad-carrier H, made as a slotted spring-tube having projecting finger-pieces h' and a closed 110 h'', substantially as set forth.

4. The combination, with the pusher B and the vertical tube A, open at the lower end 115 for the reception of the cartridge-case, of the slotted cylinder F, attached to the cylinder A, the slotted plate f, the wad-pusher G, and the movable wad-carrier H, adapted to being placed within the tube F, substantially as set 120 forth.

5. The combination, with the hopper for powder or shot and the swinging cut-off for the same, of a vertical measuring-tube beneath the hopper, a plate passing through a slot at 125 one side of the measure, a swinging valve upon the said plate, a band around the measure, and the pivot upon which the said plate and valve swing, and a bent lever pivoted upon the band and acted upon by the cut-off for moving the 130 valve, substantially as set forth.

6. The combination, with the tube A and plunger B, of separate hoppers K L, for powder and shot, the separate inclined tubes k' l',

leading from the respective hoppers and opening into the tube A at opposite sides thereof, the cut-offs, measures, and valves for the respective hoppers, and the slotted cylinder F, attached to the tube A, the removable wad-holder H, the plate f, and pusher G, substantially as specified.

7. The combination, with the vertical tube A and plunger B, of the slotted cylinder F, slotted wad-carrier H, the slotted plate f, to support the wad, the spring-fingers e, attached to the tube F, the swinging wad-pusher G in the form of a lever, and a pivot for the same at its lowest end, and a spring, h, to return said pusher to its normal position, substantially as specified.

8. The combination, with the powder and shot hoppers and the tubes for conveying away the powder and shot, of the pivoted cut-offs, the swinging bent levers and their springs, the

plates o q, the valves o' q', supported by such plates, the measures kl, the movable bands o² q² around the measures, and pivots on such bands upon which the plates and valves swing, and means for holding the bands when adjusted to regulate the powder and shot discharged, respectively, substantially as specified.

9. The combination, with the hopper for holding shot and the cut-off slide at the bottom, of the yielding finger t, within the hopper with its end adjacent to the delivery-opening in the hopper to prevent the shot obstructing the slide as it is closed, substantially as specified.

Signed by me this 29th day of May, A. D. 35
1885.
